A. G. BERGMAN,
ILLUMINATING SHELL,
APPLICATION FILED JAN. 6, 1919.

1,305,187.

Patented May 27, 1919.

UNITED STATES PATENT OFFICE.

AXEL G. BERGMAN, OF NEW YORK, N. Y., ASSIGNOR TO ORDNANCE ENGINEERING CORPORATION, OF NEW YORK, N. Y., A CORPORATION OF NEW JERSEY.

ILLUMINATING-SHELL.

1,305,187.

Specification of Letters Patent. Patented May 27, 1919.

Application filed January 6, 1919. Serial No. 269,762.

To all whom it may concern:

Be it known that I, AXEL G. BERGMAN, a subject of the King of Sweden, residing in the borough of Manhattan, city, county, 5 and State of New York, have invented certain new and useful Improvements in Illuminating-Shells, of which the following is a specification.

The purpose of my invention is to provide, 10 an illuminating shell which can be fired under the same conditions as explosive shells, making it possible to use similar firing charges and for the shell to cover the same distance as an explosive shell of the 15 same size.

A further purpose of the improvement is to afford an entirely practical construction which can be manufactured and assembled with reasonable facility and at a minimum 20 cost.

An additional purpose of the improvement is to insure sustaining the illuminant in the air while burning and to provide a novel arrangement of retarding and sustaining devices which makes it possible to utilize a sustaining parachute of requisite size in proportion to the illuminant body. 25

Another feature of the improvement resides in utilizing and arranging the parts of 30 the apparatus in such a way as to provide a strong construction, that will protect the illuminating substance and the parachute devices against any undue pressures or strains while in the shell, and also cause 35 their proper discharge from the shell.

In general, the invention consists in positioning an illuminant body at or toward the front of a shell, with retarding and sustaining devices, or parachutes, at the rear 40 end, and at the proper moment expelling the entire mass from the rear of the shell. The retarding and sustaining means consists, preferably, of a series of two, three, or more parachutes of different sizes, the smallest 45 one being located nearest to the illuminant body and coming into operation first to retard the latter, while the largest one is lo-

cated at the free end of a flexible connection which carries the illuminant body, and comes into operation last, when the speed has been materially reduced and the illuminant is in proper condition to be suspended and burnt. The parachutes being of gradually increasing size from the illuminant body toward the free end of the connection, 50 and the smaller parachutes serving to effectively retard the flight of the illuminant body, makes it possible to utilize a sustaining parachute of larger size and less heavy construction as the strain to which it is subjected is not as great as when it must perform the functions of both retarding and sustaining. The parachutes and flexible connection are joined to the illuminant body by means of a swivel which coöperates with ball bearings, thus permitting free relative movements of the connection and illuminant body and insuring the parachutes unfolding and coming into proper action at the right time. The illuminant material is housed within a thin container, preferably of sheet metal, which also serves to contain the swivel and its support, and surrounding the illuminant container are metallic bracing members which transmit practically all the 60 pressure of the expelling charge and prevent any undue pressure being brought upon the illuminant material. The parts are held within the shell by a bottom plug or plate which is provided with means for preventing its turning with reference to the shell, as the latter is fired from a gun, and it is also held in place by devices such as pins, which are readily sheared or broken by the 65 force of the expelling charge when the illuminant is to be ejected from the shell.

To these and other ends, the invention consists in certain improvements and combinations of parts, as will be hereinafter more fully described, the novel features 70 being pointed out in the claims at the end of the specification.

In the drawings—

Figure 1 is a longitudinal sectional view

of an illuminating shell built according to a preferred embodiment of my invention;

Fig. 2 is a sectional view on the line 2—2 of Fig. 1, looking upwardly;

5 Fig. 3 is a sectional view on the line 3—3 of Fig. 1, looking downwardly, with parts removed and broken away;

Fig. 4 is a sectional view on line 4—4 of Fig. 1;

10 Fig. 5 is a detail plan view of one of the spacing means;

Fig. 6 is a side elevation, illustrating the position of the illuminant body and sustaining means when suspended in the air.

15 While the structure disclosed embodies a practical adaptation of my several improvements, and has been found successful, for the purpose of this application it is used merely by way of example, and not in any

20 sense to restrict the invention to the details shown. In the present structure, A designates the shell body and B is a cap adapted to be threaded within the body A, and to contain the conventional type of time fuse,

25 which forms no part of my invention. The cap B preferably has formed as a part thereof a plate C which is relatively quite thick, as shown in Fig. 1, and the purpose of this is to prevent any likelihood of forcing the fuse from the shell body when the expelling charge is ignited, and to insure the illuminant body and its associated parts being properly ejected from the rear end of the shell, as will appear more clearly from 30 the remainder of the description. The cap B and plate C may be formed separately if desired.

The illuminant body consists of an illuminating composition or material D housed 40 with a container E, which latter is comparatively thin, and preferably formed of sheet or stamped metal. Superimposed adjacent to the base C of the cap is the expelling charge F which is surrounded by a 45 fiber ring G. The expelling charge F is shown as contained in a bag F', but may be loose in the chamber. The ring G may be of any material which will not ignite any possible loose grain of powder by friction.

50 Located between the expelling charge and the fiber ring just mentioned, and the illuminant body, is a barrier which comprises a metal disk or plate H, an outer fiber ring I and a central fiber disk J. The barrier 55 just referred to is provided with openings which are reduced adjacent to the expelling charge and enlarged adjacent to the illuminant body. This is accomplished by providing a series of small openings h in the disk

60 H, while the space i between the fiber ring I and the fiber disk J provides a sufficiently increased opening to constitute a gas expansion chamber, whereby to permit of the necessary expansion of gases when the expelling charge is ignited. The explosive gases

entering first through the small openings h and then through the enlarged opening i, are reduced in pressure, and the expansion thus created prevents undue pressure upon the illuminant material which might otherwise cause the latter to explode. The ignition of the illuminant hence takes place with safety and certainty. The fiber or other relatively soft ring G serves as a spacing member, and also by its non-grinding construction reduces the danger of explosion from a grain of powder of the expelling charge becoming lodged between two relatively movable metallic surfaces. K is a filling disk of fiber or the like such as usually employed 80 for spacing or filling purposes within the container.

The container E is bent inwardly at its inner end, as designated by L, and rests against the semi-circular spacing plates M. 85 Arranged adjacent to the latter is a fiber spacing disk m, abutting against which are the center cylindrical plates N, forming a cylinder within which the parachute devices are housed, as will presently appear more 90 clearly. Inasmuch as the container E is rather frail, and not sufficiently strong to withstand the pressure of the expelling charge, I arrange around it a plurality of bracing members, preferably in the form of 95 semi-cylindrical plates e which are co-extensive lengthwise with the container E or longer than the latter. The plates e abut the fiber ring I at one end of the metal spacing plates M at the opposite end, and transmit 100 the force of the explosion charge to the plates M and N. In this manner, the illuminant material itself is relieved of any excessive pressure while being expelled from the shell.

105 The illuminant body is governed by retarding and sustaining means, which—in the illustrated embodiment—comprise three parachutes O, O² and O³, all secured to a common connection O⁴ of any suitable flexible material such as wire, cord or a chain. The parachute O³ is the largest one of the series and is arranged at the free end of the flexible connection O⁴, the latter being secured to the illuminant body at its opposite end, and the parachutes O² and O are of gradually decreasing size. In the housing of these parts within the shell, the parachute O³ is folded first into as small a mass as possible, and the connection O⁴ and the remaining parachutes are then wound about the parachute O³. Consequently, when the parts are expelled from the shell, upon unwinding, the smallest parachute O comes 115 into action first. This is of such small size as to prevent its being readily torn or destroyed by the sudden strain to which it is subjected, while at the same time it suffices to impart a retarded movement to the illuminant body. Upon the operation of the 120

125 illuminant body. Upon the operation of the 130

next larger parachute, the flight of the illuminant body is further retarded, until by the time the sustaining parachute O^3 comes into action, the movement is so slight as to obviate unduly straining or tearing the fabric of the large parachute. The latter can consequently be made of a thinner, and less bulky material, and this makes it possible to obtain a greater expanse of sustaining surface in the parachute and consequently to hold the illuminant body suspended for the required time of illumination. It is within the province of my invention to utilize two, three or more than three parachutes, and the important essential upon which the proper operation of the apparatus depends is a parachute of small cross-section which acts in the first instance to slow up the illuminant body until it attains such a speed as to permit the larger sustaining parachute to come into action without danger of breaking it.

It is, furthermore, highly desirable that a freely movable connection be had between the illuminant body and the flexible connection O^4 , and to this end, I provide the latter with a swivel P which is arranged within a socket portion Q . The socket portion Q is held within the container E by the inwardly bent end portion L , and has a flange q upon which are supported a series of balls q^2 , and against which engages the head of the swivel P . The socket portion Q is recessed at q^3 to receive a closure in the form of a plate q^4 . The plate last mentioned is frictionally engaged in the recess q^3 , and separates the illuminant material from the interior of the socket Q and from the swivel. The parachute retarding and sustaining devices being wound up in the manner already described, are housed within the semi-cylindrical plates N , which serve to protect the fabric of the parachutes, and to transmit the explosive force of the expelling charge.

R designates a bottom plug or plate engaged in a recess in the end of the shell, and resting against the adjacent ends of the semi-cylindrical plates N and the lead or other gas check ring r . The plug R is preferably held within the shell, until the expelling charge is exploded, by forcing it into the shell with a driving fit. This construction also tends to make a gas tight fit so as to avoid ingress of the gases of the propelling charge to the interior of the shell. I may also employ pins r^2 which extend transversely through openings in the wall of the shell and into corresponding openings in the plug. These pins are preferably of copper or other similar soft material which is adapted to be sheared or broken to release the plug R when the expelling charge is ignited. The shell partakes of a rotary motion as it leaves a gun, and this is likely to cause a relative turning tendency between

the shell and the plug R . To overcome this, I provide these parts with oppositely disposed cut-away portions, forming recesses extending longitudinally of the shell body. These recesses are preferably of cylindrical formation, although they may be otherwise constructed, and are adapted to receive pins r^3 of steel or like hard material, constituting a rigid locking key. These pins are driven into the recesses and held frictionally with sufficient force to avoid dropping out; they constitute keys to prevent turning of the plug R within the shell body.

In assembling the parts heretofore described, starting with the shell body and the cap B attached thereto, with the time fuse omitted, the fiber ring G is first adjusted in place through the bottom, and thereafter the plates H , I and J are positioned. Following this, the illuminant body is inserted with the surrounding bracing members or plates e , after which the plates M , disk m , and plates N are inserted. Finally, the wound-up parachute devices are positioned within the plates N , sufficient slack or unwound part of the connection O^4 being left to permit this, and then the plug R is inserted in the end and the shearing and locking pins driven into engagement with it.

In the operation of the shell, the time fuse being set in the usual manner in this class of devices, the expelling charge is ignited at the end of the period for which the time fuse is set. Upon ignition of the charge, it forces all of the parts behind it out through the rear end of the shell, while the latter is traveling forwardly, the pins r^2 being severed by the explosive force to release the bottom plug R . The illuminant body is ignited by the firing of the expelling charge and as soon as the parts are free of the shell, the impetus of the illuminant body at once starts to unwind the flexible connection, and brings into play the small parachute O . Further unwinding of the connection opens the parachute O^2 which acts together with the first mentioned parachute to materially retard the travel of the illuminant body. Finally, the connection is entirely unwound and the parachute O^3 is opened, by which time the speed of the illuminant body is sufficiently slow to prevent tearing the sustaining parachute which gradually falls, and maintains the illuminant body properly suspended and in approximately one position until the illuminating material is entirely consumed.

In order to hold the particles of the illuminant body together, and prevent the body from disintegrating, upon expansion of the container E , or from other cause, the mass of illuminant material has a reinforcing member embedded therein. Preferably, this is in the form of a coil S of soft or pliable

metal such as copper, which can be compressed with the plastic mass when the latter is molded into the finished shape. The coil S may be anchored at one end, as by a head s engaging a recess in the end of the container E. The reinforcing member may take other forms, or be of different materials depending upon the construction and form of the illuminant body.

10. The parts which I have described may be otherwise constructed, and modified as to details, without departing from the purposes or essential features of my invention, and it is intended that the claims of this application shall cover any such changes as come within the underlying features and intended scope of the invention.

What I claim is:—

20. 1. The combination with an illuminating shell, of an illuminant body, and means for retarding and subsequently sustaining the illuminant body consisting of a flexible connection having one end attached thereto and a plurality of parachutes attached to the connection at different points between its free end and the illuminant body, one of said parachutes acting to retard the illuminant body and another to sustain the same.

25. 2. A structure according to claim 1, characterized in that said parachutes are of different sizes, the largest one being located at the free end of the connection and the smallest one located nearest to the illuminant body.

30. 3. A structure according to claim 1, characterized in that said parachutes are of different sizes, the largest one being at the free end of the connection and the smallest one located nearest the illuminant body, and the 40 connection and parachutes being wound from the free end, whereby when the illuminant body is ejected, the smallest parachute comes first into action, to retard its flight, and the largest parachute comes into 45 action last to sustain the parachute.

35. 4. The combination with an illuminating shell, of an illuminant body, a flexible connection having one end attached to said body, and a series of parachutes attached to 50 said connection at different points, and of constantly increasing size from the illuminant toward the free end of the connection, whereby the smaller of said parachutes comes first into action to retard the illuminant.

55. 5. The combination with an illuminating shell, of an illuminant body, sustaining means for the illuminant body, a flexible connection for the sustaining means, a swivel 60 carried by the illuminant body and attached to one end of the flexible connection, and ball bearings for said swivel.

6. The combination with an illuminating shell, of an illuminant body, sustaining

means for the illuminant body, a flexible 65 connection leading to the sustaining means, a socket member carried by the illuminant body, ball bearings in the socket, a swivel joined to said flexible connection and mounted in the socket member in engagement with 70 said ball bearings, and a closure separating the socket member from the illuminant.

7. The combination with an illuminating shell, of an illuminant body, an expelling charge, and a barrier between the expelling 75 charge and the illuminant body, the barrier having openings extending therethrough which are reduced adjacent to said charge and a gas expansion chamber adjacent to the illuminant body, into which said openings lead.

8. The combination with an illuminating shell, of an illuminant body, an expelling charge, and a metal wall located adjacent to said charge and having a series of small 85 openings therein, and a separable wall located in contact with a steel portion of the shell, and between said metal wall and the illuminant body, and having a large opening therein, said separable wall formed of 90 a material which is substantially softer than steel.

9. The combination with an illuminating shell, of an illuminant body, an expelling charge, a metal wall located adjacent to 95 said charge and having a series of small openings therein, and a fiber wall located between said metal wall and the illuminant body and having a large opening therein.

10. The combination with an illuminating shell, of a cap portion, an illuminant body, an expelling charge arranged adjacent to the cap portion, a metal spacing wall between said charge and the illuminant body, and a ring surrounding the charge 105 and located between the cap portion and said metal wall, said ring contacting with a steel portion of the shell and being formed of a material which is substantially softer than steel.

11. The combination with an illuminating shell, of a cap portion, an illuminant body, an expelling charge arranged adjacent to the cap portion, a metal spacing wall between said charge and the illuminant body, 115 and a fiber ring surrounding the charge and located between the cap portion and said metal wall.

12. The combination with an illuminating shell, of an expelling charge, an illuminant 120 body including a thin container, and metallic bracing walls made in longitudinal sections, said walls being co-extensive lengthwise with the container and acting to transmit the explosive force of the expelling 125 charge and to relieve the illuminant body from excessive pressure.

13. The combination with an illuminating

shell, of an expelling charge, an illuminant body including a thin container, and a longitudinal expansible metallic bracing wall co-extensive lengthwise with the container 5 and acting to transmit the explosive force of the expelling charge and to relieve the illuminant body from excessive pressure, said bracing wall being separable from the illuminant body whereby said body is freed 10 from the weight thereof after expulsion from the shell.

14. The combination with an illuminating shell and an expelling charge, of a bottom plug, the plug and shell having oppositely 15 arranged cut-away portions forming openings extending longitudinally of the shell, and locking pins positioned in said openings and preventing relative turning of the shell and plug.

20 15. An illuminating shell for rifled guns having a rotating band, said shell having a body portion, an expelling charge, a plug adapted to be forced from said body portion by said charge, and means connecting 25 the body portion and plug and acting to prevent relative turning of said parts during rotation of the shell, said means exerting greater resistance against relative rotation than against axial movement.

30 16. The combination with an illuminating shell and an expelling charge, of a bottom plug, means connecting the plug and shell, acting to hold them together and adapted to be severed to permit the plug 35 to be forced out by the expelling charge, and additional devices acting to prevent relative rotation of the shell and plug.

40 17. The combination with an illuminating shell, of an illuminant body arranged toward the front end of the shell, parachute sustaining means arranged toward the rear end of the shell, and connected to the illuminant body, and an expelling charge located in front of the illuminant body and 45 adapted to eject the said illuminant body and the parachute sustaining means from the rear end of the shell.

50 18. The combination with an illuminating shell, of an expelling charge, an illuminant body consisting of a thin container, metallic bracing walls co-extensive with said container and acting to transmit the explosive force of the expelling charge, a socket member held within the illuminant body by said 55 container, ball bearings in the socket member, a parachute sustaining device, and a swivel connected thereto and located in said socket member in engagement with the ball bearings.

60 19. The combination with an illuminating shell, of an illuminant body, means for retarding the flight of the illuminant body, means for sustaining the illuminant body while burning, and devices acting to simul-

taneously eject the retarding and sustaining means from the shell.

20. The combination with an illuminating shell, of an illuminant body, means for retarding the flight of the illuminant body, and means arranged in a line with the retarding means for sustaining the illuminant body while burning.

21. The combination with an illuminating shell, of an illuminant body, means for retarding the flight of the illuminant body, means for sustaining the illuminant body while burning, and a single supporting member for the retarding and sustaining means.

22. The combination with an illuminating shell, of an expelling charge, an illuminant body including a thin container, and separable semi-cylindrical bracing walls arranged around the container, co-extensive therewith lengthwise, and acting to transmit the explosive force of the expelling charge 85 and to relieve the illuminant body from excessive pressure.

23. The combination with an illuminating shell, of an illuminant body arranged toward the front end of the shell, retarding 90 and sustaining means arranged toward the rear end of the shell and connected with the illuminant body, and an expelling charge located in front of the illuminant body and acting to eject said illuminant body with the 95 retarding and sustaining means from the rear end of the shell.

24. The combination with an illuminating shell, of an illuminant body arranged toward the front end of the shell, parachute 100 devices arranged toward the rear end of the shell and connected to the illuminant body, an expelling charge located in front of the illuminant body, and adapted to eject the illuminant body and parachute devices from 105 the rear end of the shell, a plug at the rear end of the shell, a barrier between the expelling charge and the illuminant body, bracing plates surrounding the illuminant body and engaging said barrier at the front end, spacing 110 means engaging the rear ends of said bracing plates, and bracing plates also arranged about the parachute devices and engaging said spacing means at one end and said plug at the opposite end, whereby the 115 pressure of the expelling charge is transmitted from the barrier to the plug through said bracing plates without imposing any strain on the illuminant body or on the parachute devices.

25. An illuminating body having a container, means connected to said container for supporting said body and said body having a reinforcing member embedded therein for maintaining the continuity of the unconsumed portion thereof during burning.

26. An illuminating body having a container, means connected to said container for

- supporting said body, and said body having a reinforcing member embedded therein for maintaining the continuity of the unburned portion thereof during burning, the reinforcing member being attached to the container.
27. An illuminating body having a reinforcing coil embedded therein.
28. An illuminating body having a reinforcing coil of soft metal embedded therein.

29. The combination with an illuminating body, of a container, and a reinforcing coil embedded therein and attached at one end to the container.

In witness whereof I have hereunto signed 15
my name.

AXEL G. BERGMAN.

Witness:

M. E. HARLAN.
